CLAIM

The ornamental design for a personal computing device display screen with a graphical user interface for trading platform, as shown and described.

DESCRIPTION

FIG. 1 is a front view of a personal computing device display screen with a graphical user interface for trading platform of a first embodiment of the present invention;

FIG. 2 is a front view of a personal computing device display screen with a graphical user interface for trading platform of a second embodiment of the present invention; and,

FIG. 3 is a front view of a personal computing device display screen with a graphical user interface for trading platform of a third embodiment of the present invention.

The outermost broken line showing the display screen forms no part of the claimed design. The other broken line showing of the text and graphical elements form no part of the claimed design.

1 Claim, 3 Drawing Sheets
